UNITED STATES PATENT OFFICE.

MARTIN RODGERS, OF NEW YORK, N. Y., ASSIGNOR OF ONE-HALF TO ALEX. TAYLOR & CO., INC., OF NEW YORK, N. Y., A CORPORATION OF NEW YORK.

REPAIR DEVICE.

1,355,781.

Specification of Letters Patent. Patented Oct. 12, 1920.

Application filed January 20, 1920. Serial No. 352,796.

To all whom it may concern:

Be it known that I, MARTIN RODGERS, a citizen of the United States, and a resident of the city of New York, borough of Manhattan, in the county and State of New York, have invented a new and Improved Repair Device, of which the following is a full, clear, and exact description.

The present invention relates to improvements in apparatus for repairing flexible tubes and the like, and it pertains more particularly to means for repairing the inflation tubes of inflatable bodies.

It is an object of the invention to provide a means by the use of which tubes of the above-mentioned character may be readily applied to inflatable bodies.

Footballs, basket-balls, and the like, have internally of their cover, what is commonly called a "bladder" and said bladder is inflated by means of a flexible tube. The usual manner of closing these tubes is to fold them over intermediate of their ends and wrap them with a suitable strand or cord, rubber, or the like. This treatment being constantly applied, the tube cracks and becomes leaky, and it is sometimes desirable to replace this tube which without the use of special apparatus is a difficult operation.

Referring to the accompanying drawings—

Figure 1 is a fragmentary view of a portion of a bladder of the aforementioned character showing the application of a device constructed in accordance with the present invention;

Fig. 2 is a longitudinal sectional view of the tube showing the method of applying the same to the bladder, and

Fig. 3 is a similar view showing the method of withdrawing the placing apparatus.

Referring more particularly to the drawings, the reference character 5 designates a bladder and 6 represents a nipple which is secured thereto, said nipple having a circular flanged piece 7 of relatively thin material, by means of which it is secured to the bladder 5 with cement or by a process of vulcanization.

The device of the present invention consists of a sleeve 8, the upper end of which is provided with a reduced portion 9, the other end being open. Leading from the reduced end is a cord 12, said cord being provided with a handle 13 by means of which it is manipulated. While in the present instance the element 12 has been described as a cord, it is apparent that a wire or other similar flexible material may be employed with equal facility. In use, this device is inserted over the end of the nipple 6, as indicated in Fig. 1. After this has been accomplished, the length of tube 15 which it is desired to secure to the nipple 6, is passed over the cord 12 and is positioned over the sleeve 8, by means of which the positioning of the length of tube 15 is facilitated. The nipple 6 being first provided with a coating of suitable adhesive material, such as cement, the tube 15 is drawn down over the member 8 as shown in Fig. 2, until its lower end engages the piece 7, as indicated by the reference character 16 in Fig. 2. The cement by means of which the tube 15 is secured in place is indicated by the reference character 17, and after the tube 15 has been secured to the nipple 6 by means of the cement and the same has sufficiently set, to temporarily secure the tube 15, by subjecting the cord 12 to a pulling action through the medium of its handle 13, the metallic member 8 is removed from the end of the tube 15, as indicated in Fig. 3.

From the foregoing, it will be apparent that the present invention provides means by which two flexible tubes may be placed one within the other for the purpose of securing one to the other, and, at the same time, provides means which is detachably carried by one tube for greatly facilitating such an operation.

Claims:

1. A device of the character described comprising a metallic body having an open end and a reduced end, and flexible operating means secured to the reduced end of said metallic body.

2. A device of the character described comprising a metallic body having an open

end and a reduced closed end, and suitable operating mechanism secured to the reduced end on the interior of the metallic body.

3. The method of uniting flexible tubes, which consists in inserting one of the tubes within the open end of a hollow rigid body and passing the flexible tube to be attached to the first-mentioned tube over said hollow

rigid body and subsequently removing said hollow rigid body from the first-mentioned tube longitudinally through the second-mentioned tube, substantially as described.

MARTIN RODGERS.
